T. HILL

MOP

Filed July 29, 1927

Patented July 10, 1928.

UNITED STATES PATENT OFFICE.

THOMAS HILL, OF DETROIT, MICHIGAN, ASSIGNOR TO DAN H. GILCHRIST, OF DETROIT, MICHIGAN.

MOP.

Application filed July 29, 1927. Serial No. 209,201.

This invention relates to improvements in mop structures and particularly to an improved mop of the type wherein there is provided a cloth-carrying mop head pivotally mounted upon the handle to lie normally within the axial line of the handle or to be swung outwardly at an angle with respect to the handle.

The object is to provide a mop structure of this character wherein the head is so mounted upon the handle and provided with cooperating mechanism adapted to releasably lock the head at an angle with respect to the axial line of the handle for convenient wringing of the mop cloth. A further improvement lies in the provision of readily accessible and manipulable mechanism for twisting the mop cloth to accomplish the wringing thereof. Such objects, together with other meritorious features and advantages will more fully appear from the following description of the illustrative embodiment of my invention exhibited in the accompanying drawing and from the appended claims.

In the drawing:

Fig. 1 is a perspective of my improved mop structure partly broken away.

Fig. 2 is a side elevation of the structure exhibited in Fig. 1 with the mop head swung out of the plane of the handle and releasably locked in such angular position.

Fig. 3 is a sectional view taken on line 3—3 of Fig. 1.

Fig. 4 is a fragmentary sectional view taken longitudinally of Fig. 1.

Fig. 5 is a horizontal sectional view through the handle taken on line 5—5 of Fig. 1.

Fig. 6 is a sectional view taken on the same line as Fig. 5 with the parts partly disengaged.

My improved mop structure has a handle portion 10 which is provided with a mop head that carries the mop cloth. The handle has at one end a metal ferrule 12 which has spaced flaring arms 14.

A mop head is pivoted at 15 to these arms 14. This head comprises a pair of spaced flaring arms 16 which are spanned at their outer ends by a trough-shaped cloth engaging part 18. The head includes a second trough-shaped cloth engaging part indicated as 20 and which is adapted to be received within the first cloth engaging part and be-

tween which cloth engaging parts a cloth 22 is disposed. The cloth engaging part 20 has a threaded shank 24 which extends through the cloth engaging part 18 and upon which is threaded a tightening nut 26 whereby the two cloth engaging parts may be held together to grip the cloth in place between them.

A third cloth engaging part 28 is provided which has a shank or handle 30 that extends through the threaded shank 24 of the cloth engaging part 20 and extends rearwardly along the ferrule 12 of the mop handle. This handle 30 is adapted to be received within a groove 32 formed in the ferrule 12, the opposite sides of which groove exert a yielding pressure upon the handle 30 to hold the same releasably therein as appears in Figs. 5 and 6 of the drawing. The handle 30 is provided with a laterally extending crank portion 34 through the use of which it may be easily rotated as hereinafter described.

The entire head assembly is adapted to swing upon the pivot 15 with respect to the handle. It is shown in the normal position in Fig. 1 in solid line. In Fig. 2 it is shown as having been swung out of the plane of the handle and locked in such angular position. It is locked in this position by means of a part 36 which has a pair of arms 38 that are pivotally connected at 40 with the arms 16 of the head. This part 36 extends rearwardly along the ferrule and is provided with a ferrule gripping ring 42 and a spring portion 44 which is tensioned to exert a pressure normally toward the ferrule. This spring portion 44 is provided with a lug 46 adapted to be received within a recess 48 formed in the ferrule and has a saddle 50 which partially embraces and rides over the ferrule and guides the lug to said recess.

In the normal use of the mop the parts are positioned as shown in solid line in Fig. 1. When it is desired to wring the mop cloth, the head is swung to the angular position shown in Fig. 2 and the cloth engaging member 28 is rotated through the rotation of the crank 34 and the cloth is twisted. To dry the cloth, the handle 34 is moved forwardly until the cloth is tensioned and then such handle is swung into the groove 32 in the ferrule and the cloth is held at such outstretched position.

What I claim is:

1. A mop having a handle, a head pivoted

110

105

100

- to the handle and adapted to be locked within the axial line of the handle or at an angle with respect thereto, a cloth carried by the head, a rotatable cloth engaging part mounted upon the head to twist the cloth with respect to the head, said rotatable part having a handle portion extending rearwardly along the mop handle, said mop handle having a groove to receive the handle portion of the rotatable part and having means adapted to grip the same to secure it therein at any position wherein it may be disposed.
2. A mop having a handle, a head pivoted to the handle and adapted to be locked within the plane of the handle or at an angle with respect thereto, said head including a pair of trough-shaped cloth engaging members one mounted within the other, means for releasably locking said cloth engaging members together, a third cloth engaging member receivable within the inner of said pair of members and provided with a shank extending through both of them and terminating in a handle extending rearwardly along the mop handle and provided at its free end with a laterally projecting crank.
3. A mop having a handle provided with a pair of spaced arms, a head having a pair of spaced arms pivoted to the arms of the handle and having a trough-shaped cloth engaging member spanning its arms, a second trough-shaped cloth engaging member receivable within the first trough-shaped member and provided with a threaded shank extending through the first member, means engaging said shank to releasably lock said members together, a cloth disposed between said members, a third cloth engaging mem-

ber receivable within the second trough-shaped member and provided with a shank 40 extending freely through the shank of said second trough member and extending rearwardly along the mop handle, and adapted to be releasably locked therein.

4. A mop having a handle, a cloth carrying head pivoted thereto to lie within the plane thereof or to be swung out of the plane of the handle, said head provided with a part extending rearwardly along the mop handle and secured thereto to travel slidably 45 thereover as the head is swung out of the plane thereof, and means holding said part under spring pressure toward said handle, said part and handle having cooperating means adapted to automatically engage at 50 a determined slidable position releasably locking the part to the handle to hold the head swung out of the plane of the handle.

5. A mop having a handle, a cloth carrying head pivoted thereto to lie within the axial line of the handle or to be swung out of the axial line of the handle, said head provided with a part extending rearwardly 60 along the handle and having a saddle engaging said handle to guide said part thereover as the head is swung out of the plane of the handle, said part held normally under spring pressure towards said handle and adapted to automatically releasably lock therewith at a determined position to hold the head at an angle with respect to the plane of the handle. 65

In testimony whereof, I, THOMAS HILL, sign this specification.

THOMAS HILL.
